MOBILE FIRE PUMPER

Harry E. La Bour, Elkhart, Ind.

Application February 25, 1942, Serial No. 432,314

17 Claims.

(Cl. 103—87)

The present invention relates to fire pumbers, and more particularly to the mobile type of fire pumper such as is adapted to be hitched to an automobile and to be drawn thereby to the place of use.

The present invention is an improvement upon the fire pumper disclosed and claimed in my co-pending application, Serial No. 293,227, filed September 2, 1939, to which reference is hereby made.

In the development of a mobile fire pumper unit of the type adapted to be hitched as a trailer behind an automobile and hauled to the place of use, a number of important considerations are to be taken into account. First of all is the necessity for a compact and powerful engine and pump unit. The pump must be capable of taking water from any available source, such as a pond, a sump, a stream or from a fire hydrant under pressure. The pump must be capable of lifting water to it, that is to say, it must be a self-priming centrifugal pump. At the same time it must be adapted as to the strength of its relatively large chambers and as to its packing gland to withstand operating pressure when supplied from a fire hydrant.

To be of maximum utility a pumper should be compact, of low total weight and all the parts conveniently arranged for operation by a minimum number of operators, if necessary, by one man, so that an organized group or brigade is not necessary to call into use the potentialities of a motor driven self-priming centrifugal pump having the capability of throwing a stream of water to at least the second story of a building with sufficient force to smash glass windows at that height and to throw an effective quantity of water upon the fire.

In the preferred form of unit herein illustrated and disclosed the motor pump unit is capable of lifting water from a lower level as much as twenty to twenty-five feet, or even more below it, and of throwing one hundred and fifty gallons per minute with the force of water delivered at the pump of one hundred pounds per square inch, or thereabouts.

The present unit is suitable for the protection of farm buildings, small communities, country houses, summer hotels, a group of cottages and the like. It can if necessary be hauled to the fire and put into operation by one man. Specially trained personnel is not essential but is desirable.

A primary consideration in the bringing of such a unit into operation is first the ability to haul it at high speed hitched to the bumper, or to a special hitch if desired, on the rear of any standard make of automobile, and, second, to

have the unit arrive in condition for operation, that is, equipped with all the necessary parts for throwing water upon the fire, and capable of performing its intended function.

5 The pump which is here disclosed is of the self-priming centrifugal type employing a charge of liquid whereby air from the intake is entrained and discharged through the liquid in the separator to evacuate the suction pipe and to fill the pump with water. Provision is made to maintain the priming charge of liquid in the pump and to allow the pump to prime as soon as the suction hose is connected and covered with water even though the discharge hose is not ready for action. Further consideration is the convenient placement of the various parts required with ready accessibility and yet safety from loss in transit.

20 The present pumper is well balanced and has a low center of gravity. As a result the unit may travel at substantially any speed which the hauling automobile may attain and over roads which the hauling automobile may encounter. At the same time it is so constructed and organized that it may be wheeled about by hand.

25 Among the improvements which the present unit embodies in the preferred form of the fire pumper are the following:

The chassis of the unit is provided with a drop frame in front of the axle for mounting the engine within the frame at as low a level as is consistent with road clearance and safety. The engine and pump unit are compactly assembled without interfering with convenient operation and servicing of the necessary parts. The pump and engine are assembled as a unit and have a unique form of mounting on the chassis frame to insure firm mounting of the combined unit on the frame without danger of binding the operating parts of the engine and pump in assembly upon the frame. A discharge hose box is disposed at the rear of the frame and is arranged for the most rapid and convenient running out of the discharge hose to any length with the limit provided. At the same time the suction hose, which is quite heavy and is cumbersome, is mounted on the forward part of the frame, that is, mostly in front of the axle, so that the two bodies of hose tend to balance each other substantially over the single axle. The whole unit has been organized with a lower center of gravity as compared with the earlier form of device and hence it has been possible to increase the capacity and at the same time the road-ability of the unit.

The present form of unit also provides a new 50 compact form of self-priming centrifugal pump

suitable for this specific service and also suitable for other services. It employs preferably a straight bladed impeller which sweeps the channel and employs the hydraulic balance recirculating principle using a hydraulically balanced throat as per my prior issued Patent No. 1,578,236.

A valuable feature of the present form of pump is the unitary pump body formed preferably as a single casting. It provides three functional chambers, namely, a generally L-shaped inlet trap, a generally cylindrical impeller chamber, and an inverted-L-shaped separator. The trap and separator are separated within the pump body by a generally Z-shaped internal wall forming a part of the structure of the body casting 15 and being common to the two interfitting L-shaped chambers.

The connection and mounting of the motor and pump involves a novel form of bell bracket which sustains the major weight of the unit on a cross member of the chassis frame disposed forward of the axle.

With the low center of gravity and the main chassis frame disposed at or slightly below the bumper level of the hauling automobile, I have found that the handling of the unit by hand can be greatly improved by disposing the cross-bar at a level substantially above the frame. The bracket which holds this cross-bar may be disposed behind the saddle or yoke for holding the bight of the suction hose whereby the handle or cross-bar operates to insure that the hose will not become dislodged at the front part of the vehicle and lost in transit.

There are numerous other features of novelty in the pumper unit as a whole and in the construction of the pump both as a pump and as a part of the present unit which will be more apparent from the detailed description and claims hereinafter appearing.

Now in order to acquaint those skilled in the art with the manner of constructing and operating a device embodying my invention, I shall describe in connection with the accompanying drawings which form a part of the present application a specific and preferred embodiment of my present invention.

In the drawings:

Figure 1 is a top plan view as seen by the eye;

Figure 2 is a left side elevation of the unit;

Figure 3 is a top plan view of the chassis frame;

Figure 4 is a left side elevation of the same;

Figure 5 is a right side elevation of the motor pump unit shown in Figures 1 and 2 with parts shown in section;

Figure 6 is a longitudinal vertical section viewed from the right and taken through the bell bracket and pump head member between the engine and the pump;

Figure 7 is a vertical cross section taken on the broken section line 7-7 of Figure 5 showing the internal construction of the pump;

Figure 8 is a development of the main throat of the pump;

Figure 9 is a similar development of the auxiliary throat of the pump, these two latter figures, being diagrammatic;

Figure 10 is a fragmentary section taken substantially on the line 10-10 of Figure 9 to show the opening of the main discharge passageway into the separator;

Figure 11 is a vertical section of the right hand fender, as viewed from Figure 1, showing how it is secured to the chassis frame;

Figure 12 is a side elevation of the fender supporting bracket;

Figure 13 is a vertical section of the chassis frame as taken along the lines 13-13 of Figure 3;

Figure 14 is a vertical cross section of a chassis cross bar as taken along the lines 14-14 of Figure 13; and

Figure 15 is another vertical section of the chassis frame as taken along the line 15-15 of Figure 3.

Referring now to the mobile pumper shown in Figures 1 and 2, the chassis frame 1 carrying the motor pump unit 2 and various accessories, is slightly overbalanced forwardly of the axle 3. Hence, when the pumper is standing is disconnected from the hauling vehicle the chassis frame 1 requires support as by the retractible standard 5 under the tongue 4 in addition to the main support secured by the axle 3 and the rubber tired road wheels 6, 6, which are mounted freely rotatable on the spindles at the ends of the axle 3. The axle 3 has a central drop portion, as indicated at 3' in Figure 2, and the spindles on which the spindles on which the wheels 6 are mounted are connected to the chassis frame 1 through the medium of semi-elliptical springs 7, 7, which are secured to the channel bar side sills 8, 8 through the medium of the forward spring perch brackets 9, 9, and through shackles 10, 10 to the spring perch brackets 12, 12 (see Figures 3 and 4).

The side sills 8, 8 of the chassis frame (see Figures 3 and 4) are extended convergently forward at the portions 13, 13 and joined by short cross members 14 to form the tongue 4 heretofore mentioned. A bracket 15, which bracket is preferably formed of a piece of angle-iron, is welded or otherwise fastened to the cross piece 14 at the forward end of the tongue, and upon this bracket 15 there are bolted the yoke or saddle member 16 providing a U-shaped bracket forming a seat for the suction hose, as will be described later, and the stationary frame portion 17 of the detachable bumper hitch 18. The hitch 18 may be of any conventional or preferred form, and comprises in the present instance a universal joint portion 19, a clamping frame 20 having a stationary upper jaw 22 and a movable lower jaw 23 which movable jaw may be moved by means of a screw member 24, and the hand wheel 25. Additionally, the bracket 15 has attached thereto a hitch chain 26 provided with a snap hook 27, this chain being adapted to be slung around the bumper and the hook 27 hooked back in the links of the chain so as to insure coupling of the pumper to the bumper of the automobile to which the hitch 18 is intended to be connected. The chain is a safety feature. Two such chains may be provided. On the rear side of the cross member 14 there is provided a pipe bracket 28 for receiving the standard or leg 5 which has the pedestal or foot member 29 at its lower end. A pin 30 on the shaft of the standard 5 is adapted to be passed up through a slot 32 (see Figure 3) when the standard is raised, and is to be held in raised position, the pin 30 being rotated out of register with the slot 32 for that purpose.

The bracket 28 is provided with a boss 33 (see Figures 3 and 4) for receiving a clamping screw having a handle 35 for clamping a shoe held in the slot 36 inside of the bracket 28, said shoe being pressed by the clamping screw against the shank 5 of the standard, to clamp the same in adjusted position. On the forward ends of the

converging side frame members 13, 13 are mounted inverted U-shaped brackets 37, 37. A tubular cross-bar 38 is provided with studs which clamp the cross bar to the tops of the brackets 37, 37 so as to provide suitable handles for hand manipulation of the mobile pumper upon its wheels. The chassis frame at its rear end has a cross member 39 lying in the plane of the side sills 8, 8 and welded to the ends thereof. The cross bar 39 is a piece of channel member as are the side sills 8, 8, the converging parts 13, 13 and the front cross bar 14. The rear cross bar 39 is provided with openings 40, 40 through which the discharge hose box 42 is bolted to the chassis frame. At the forward end of the parallel side sills 8, a front cross bar 43 of channel cross section is suspended from and immediately below the main frame by means of gusset plates 44, 44 which are welded to the inside of the channels of the side frame members 8 and to the flat side of the web of the cross bar 43, as is more clearly shown in Figure 13. Thereby the cross bar 43 is suspended below and welded to the side frame members 8, 8 and to their extensions 13, 13. A second cross bar 45, similarly made of channel bar is suspended by gusset plates 46, 46 from the sills 8, 8, as will more clearly appear in Figure 15. These parts are welded in place.

A pair of battery brackets 47, 47 are welded to the cross bars 43 and 45 and extend toward each other. Preferably a wooden plate or board is bolted to these brackets 47, 47, such a board being indicated at 48 in Figure 2. The cross members 43 and 45 are connected together by a brace 49 which is formed of channel bar, and is welded to the bottom flanges of the bars 43 and 45 in the median longitudinal plane of the frame. In the specific embodiment shown wherein the engine is a four-cylinder air cooled engine, of known type, the brace 49 forms the support for the front end, that is the flywheel end of the engine through the medium of a supporting plate 50, a spacer block 52 and a bolt 53, such details being shown more clearly in Figure 5. The plate 50 is bolted to the flanges of a cross channel member 54 which is a permanent part of the engine.

The right hand side sill shown at the top of Figure 3 has a bracket 55 for supporting auxiliary apparatus, such as a fire ax. The front cross member has holes 56 for bolting thereto a crank bracket 57 shown in Figure 5 and a filler block 58, shown more clearly in Figure 4 and Figure 14, provides an anchorage for the downwardly extending foot 59 of the said crank bracket. The crank bracket 57 supports the hand crank 60 in convenient position to be applied to the flywheel of the engine for hand cranking the same. This crank 60 is disposed between the converging frame portion 13, space being here provided for operation of the crank to start the engine by hand. When the engine pump unit is made removable from the chassis, the crank bracket and crank are carried on the crank case of the engine.

The cross member 45 has holes 62, 62 formed through the top flange for receiving bolts to which the feet 63, 63 of the bell bracket 64 are connected. The bell bracket 64 rigidly connects the crank case of the engine, and the frame of the pump and forms a part of the pump, as will be later described, but it will now be seen that the engine and bell bracket with connected pump have a three-point mounting which may be more

or less resilient through the supporting plate 50 at the front and a fairly solid two-point mounting on the cross member 45 of the sub-frame. The sub-frame comprises the cross members 43 and 45 and the connection brace 49 all slung below the main frame.

A transverse member 65 in the form of an angle-bar with the vertical flange thereof engaging and welded to the bottom flange of the side sills 8, 8 provides a horizontal ledge 66 upon which the discharge hose box seats and is supported. The ends of the angle-iron cross bar 65 are welded to blocks 67 and these in turn are welded to the bottom of the sill members 8, 8 whereby the said cross member 65 is suspended below the plane of the sills 8, 8. An angle-shaped bracket 68 is clamped to the vertical flange 69 of the angle bar cross member 65 and this supporting bracket 68 has bolt holes 70, 70 for engaging and clamping to the foot 72 of the main pump body, as is shown in detail in Figure 5. Supporting plates 73, 73 are welded to and span the tops of the cross members 45 and 65 to provide support for a tool box 74 and for the hand fire extinguisher 75 which are suitably clamped to the respective plates 73, 73.

The wheels 6, 6 are provided with arched and crowned fenders, the detailed mounting of which is shown in Figure 11. The fender is provided with a skirt 77 which is generally semi-circular in outline, and this skirt is welded to the margin of the channel shaped crown of the fender. Along the lower inner edge of the skirt 77 is an angle bar 78 with its vertical leg pinned or spot welded to and disposed across the lower edge of the skirt and adjacent flange of the crown, and its horizontal leg clamped at the end to the front and rear spring perch brackets 9 and 12, respectively, suitable holes 79 and 80, respectively, being provided on these spring perches for holding of the horizontal leg of the angle bar 78 thereto, as will be apparent from Figures 3 and 11.

Hose and fender supporting brackets 82, 82 shown in detail in Figures 11 and 12 perform the dual function of providing a saddle for the ends of the suction hose 83, 83, two standard 12-foot lengths of which are provided. These bracket members 82 are U-shaped, with a longer limb 84 thereof extended up to substantially the top of the fender, and there provided with a slotted bolt hole for receiving a bolt 85 for clamping the upper part of the fender and its skirt to the said bracket 82. At its lower end, the bracket 82 is welded in place to a short section of angle-bar 86 shown in Figures 11 and 12, which section of angle-bar 86 is in turn welded to the outside and upper edge of the side sill member 8. Additionally, the rear portions of the skirt and flange of the fenders 80 lie against the adjacent edge of the rear hose box 42 and bolts extend through adjacent walls of the rear hose box 42 and the fender skirts for securing the fenders to the hose box 42. The bracket 82 has leather or other flexible straps 87, 87 fastened thereto, as by means of rivets passing through the holes 88 and 89 for strapping the ends of the hose securely in brackets 82. Likewise straps 87 are connected to the ends of the U-shaped bracket 16 of the front of the tongue of the frame for securely holding the hoses in place. The top length of section hose 83 is provided with a strainer 90, and the opposite end of the hose is provided with a coupling 92 by which it may be connected to the second length of hose 83, or 70 it may be coupled to the suction fitting of the

pump later to be described. It will be observed that the suction hose is bent into U-shape, dropped into the front saddle 16, and into the side saddles or brackets 82, and strapped in place, and it is then securely held, and even if the strap should break, the disposition of the hose in the front saddle 16 under the handle bars 38 renders it quite unlikely that the hose will be dislodged, for it is necessary to raise a free end of the hose out from behind the wheel fender 76 and thence from under the handle bar 38 before the hose can be taken out of the front saddle 16. This is a feature of safety which is highly desirable, for obviously the loss of the suction hose in transit would be intolerable. The discharge hose box 42 has an upper main portion 93 extending out beyond the sides and end of the chassis frame and it has a well portion 94 extending down through and within the frame. Thus a maximum of space is provided. The hose box preferably provides room for about 500 feet of standard 1½ inch discharge hose or a less amount of 2½ inch hose, and the hose is arranged therein for maximum convenience in running out the same. The free end which bears the nozzle 95 is coiled in a double reverse coil 96, so that this length of hose may be run out without twisting, and the first length is coupled to the next length 97 by the coupling 98 shown in Figure 1, the second length being folded back and forth, and paying out of the rear end of the hose box, so that twisting of the hose is avoided and the next available joint readily convenient. The hose box is covered by a canvas or waterproof fabric cover, which is fastened to the rear edge of the box 42 and it may be rolled back as shown at 100 in Figure 1. When in place over the top of the hose box 42, the cover 99 is held in place by straps 102 and buckles 103, suitably hooked into eyes on the rear of the hose box.

The motor pump unit 2 comprises an air cooled four cylinder high speed motor 104 directly connected to a self-priming centrifugal pump 105 mounted as aforesaid on the chassis frame within and below the top level of the chassis frame. The clearance between the sub-frame and the ground is substantially the same as that of the axle 3' and is comparable to that prevailing in automotive practice for passenger cars. It is to be observed that it is within my invention to mount the engine pump unit as a removable unit upon the chassis frame where that is desired, since it is within the convenient capability of two men to lift and transport the same through the provision of suitable handles, as described in my copending application, Serial No. 293,227, filed September 2, 1939. The engine 104 has a flywheel cage 106, the cage constituting also a blower for air cooling the engine cylinders and heads. At its opposite or rear end, the engine crank case, which is concealed by the protected casing, as illustrated in Figures 5 and 6, has a boss 107 through which a crank shaft 108 extends, the said crank case being provided with threaded sockets for receiving the studs 109. These studs 109 pass through a ring 110 formed on the rear end of a bell bracket 64, and by a ring of these studs 109 the said bell bracket is securely clamped to the engine frame or crank case.

At its opposite end, the bell bracket 64 has a cylindrical plug-like portion 112 which fits the cylindrical bore 113 of the main pump body casting 114. The plug-like member 112 terminates in the flat annular wall 115 which forms the back plate of the impeller chamber of the pump. The

clamping flange 116 is clamped by means of the studs 117 to the flat face of the flange 118 which projects outwardly around the bore 113. A suitable gasket is interposed to make a fluid tight joint. The back plate 115 has an integral boss or hub 119 which is bored to pass the shaft 120 of the impeller 122 and counterbored to form a packing gland recess for receiving the packing 123. The impeller shaft 120 is axially bored to receive the holding bolt 124 which is threaded into the adjacent reduced end 125 of the engine crank shaft 108. The bolt 124 is covered by a tapered plug. The two shafts are keyed together by a Woodruff key or equivalent means, as indicated at 126. The impeller shaft 120 is thus rigid with crank shaft 108 and is supported by the bearings of the said crank shaft.

The bell bracket 64 includes an intermediate wall 126 which forms a transverse diaphragm suitably braced as by the webs 127 to receive the thrust of the threaded spring barrel or sleeve 128 which is threaded in a central opening formed in the diaphragm 126. This spring barrel 128 has an inwardly extending flange 129 for receiving the recoil of the compression spring 130. The other end of the spring 130 bears against the auxiliary gland follower 132 which bears against the packing 133 disposed in a gland recess formed in the main follower 134 which in turn bears against the packing 123 in the hub 119. The main gland follower 134 is hollowed out centrally to receive grease through the tube 136 from the grease cup 137 which in Figure 6 is shown substantially in the plane of the paper whereas it would occupy a position substantially 90° thereto in practice. The bell bracket 64 has openings at the sides for rendering the packing gland readily accessible. This packing gland construction is disclosed in my copending application Serial No. 385,888, filed March 29, 1941, and need not here be elaborated upon as reference is made to the aforesaid copending application for a full description of the same. Suffice it to say that the spring barrel 128 has a head 135 provided with suitable surfaces by which it may be engaged by a wrench or other suitable tool for turning it upon its threads. The auxiliary follower 132 has a groove which registers with an opening in the head 135, so that the threaded sleeve 128 may be run to the right, as viewed in Figure 6, with the follower 132 pinned to the sleeve as by a pin inserted through the hole in the head 135 and into the groove in the follower 132 to permit the sleeve and follower 132 to be retracted to the right sufficiently to allow repacking of the fibrous packings 133 and 123. It is to be observed that the sleeve forms the back stop for preventing blowing out of the main packing 123 in the event that the pump should receive its liquid supply under pressure as when the suction connection is coupled to a fire hydrant or the like.

The plug-like extension 112 of the bell bracket 64 serves both as a pilot for bringing the pump body 114 and said bell bracket into register, and it serves as additional supporting means for taking the shear load off of the studs 117 by which the two parts are clamped together. The space within which the impeller 122 rotates is termed the impeller chamber, the casing thereof being formed by the back plate 115, the front plate 138 and the peripheral wall, which defines the bore 113. The front plate of the impeller casing has a central intake opening 139 which opens into the bottom of a chamber 140 in the casting

114, this chamber 140 constituting the intake trap of the pump. The impeller 122 which is shown in end view in Figure 7 preferably has straight blades which sweep the channel in which the impeller runs, with substantially no more than mechanical clearance.

The main pump body casting 114 is somewhat barrel shaped, having a front wall of double convex shape as indicated at 142 in Figure 5 and a similarly double convex shaped back wall 143. 10 The hollow space of the main body casting 114 is divided by a wall which consists of an upper horizontal flat wall 144, a lower horizontal cylindrical wall 145 and a flat vertical wall 146 joining the two walls 144 and 145 at their inner ends. 15 This divides the space in the hollow casting 114 as may be seen from Figure 5 in two generally L-shaped spaces, the lower of which, indicated at 140, is the intake trap, and the upper of which as indicated at 147 is likewise L-shaped but in reverse position, that is to say, it has the horizontal leg thereof at the top, and the vertical leg extending downwardly, whereas the intake trap has the horizontal leg at the lower end, and the vertical leg extending upwardly. The discharge chamber or separator 147 is disposed above the impeller casing, and communicates therewith through a main discharge passageway 148 and throat 149, and communicates additionally through an auxiliary discharge passageway 150 and a corresponding throat 152.

Figure 8 is a diagrammatic development of the main passageway and its restricted throat 149. Likewise, Figure 9 is a diagrammatic development of the auxiliary discharge passageway 150 and its throat 152. The particular construction and arrangement of these throats in a pump of this character is described and claimed in my copending application Serial No. 289,757, filed August 12, 1939, to which reference for a full description is here made. It will be observed that the throat 149 lies in such position that the passageway 148 leading therefrom is substantially a tangential passageway for the discharge tangentially of liquid by the impeller 122 and at its upper end the wall defining the discharge passageway 148 runs substantially tangent to the curved surface of wall 153 of the drumlike separator portion of the separator chamber 147. That is to say, the main vertically extending part of the separator chamber 147 is provided with a substantially cylindrical wall, the axis of rotation of which cylindrical wall is substantially horizontal. Communicating with this drumlike portion is the forwardly extending portion 147a of the said separator 147, as shown in Figure 5 and Figure 7.

The auxiliary discharge passageway 150 which serves as a priming passageway for the return of liquid to be mixed with air in the impeller chamber during the priming operation of the pump communicates between substantially the top of the impeller chamber and the bottom of the separator chamber 147. An overhanging wall or hood 155 protects the pump from losing its vacuum by air striking down through the passageway 150 during priming. The overhang of the hood 155 is such that the movement of liquid into the passageway 150 is substantially horizontal, and there is not the tendency for a whirlpool to suck air down through the center and thus break the prime, as would be the case if the passageway 150 opened in a vertical direction. The hood 155 may be extended to a greater or less degree sufficiently to secure the desired ac- 75

tion of preventing the striking of air down through the passageway 150 under suction in the impeller chamber, when there is no great depth of liquid above the passageway 150. It is to be observed that when the pump is priming the liquid is all pulled out of the intake trap 140 and driven over into the separator 147. But even so, it is highly desirable to guard against air striking back in a situation where, due to the disturbed condition of the liquid, and not too great a volume of the same having been trapped within the spaces of the pump, the pump is required to operate on minimum liquid.

It is to be observed that the main discharge passageway 148 opens up into the drumlike portion of the separator 147 adjacent the junction of the rear wall 143 and the side wall 156. (See Figures 10 and 5.) Also, it will be seen from Figure 5 that the rear wall 143 curves over towards the left as viewed in Figure 5, which brings the upper part of the end wall 143 over substantially into the plane of the main discharge throat 148, the result being that as the stream of mixture discharged by the pump tends to hug the circular wall 143 and rises to the top, it is pushed over to the left, as viewed in Figure 5, or upwardly away from the wall 143, as viewed in Figure 10, so as to throw the return loop of the stream out of the plane of the hood 155 and the auxiliary discharge throat 150. In brief, the return loop of liquid coming down towards the bottom of the separator chamber 147 tends to be brought out of register with the plane of the discharge passageways into the region of the reference numeral 145 in Figure 5, so that the stream of mixture will have a maximum opportunity to free itself of the entrained gas, such as air, both in the whirling centrifugal separation effected by discharge of the stream along the cylindrical wall, and by gravity separation in the pool which is maintained in the bottom of the separator space 147. In Figure 10, the channel in which the tips of the blades of the impeller 122 run is indicated by the dotted lines 154, and it will be seen that the main throat 149 is narrower than the channel width. Likewise, the throat 152 is narrower than the channel width for the purposes of maximum efficiency of discharge of liquid during liquid pumping, as described in my copending application above referred to.

The forwardly extending or offset portion 147a of the separator chamber allows the gas freed in the disentraining operation in the separator to pass upwardly through the discharge elbow fitting 157, and then out if the said fitting is open to atmosphere. Preferably an air vent which closes when water strikes it, and which may be in the form of a well known air vent valve such as is employed on steam radiators, permits the escape of the disentrained air to atmosphere, so long as liquid does not fill the discharge chamber or separator 147. Another effective method of disposing of the disentrained air is to provide a small constantly open tube, such as a copper tube indicated at 158 in Figures 1 and 5. This tube may be constantly open, and be directed down upon the ground. Due to the length of tubing and the small bore, sufficient friction is introduced to the flow of liquid that the loss of liquid is inappreciable, whereas the tube offers no substantial resistance to the flow of the air which is discharged during the priming operation. This air vent may be connected to the elbow 157, particularly for the advantage which it pro-

vides in taking the air vent out of the region of rapidly moving water during the priming operation. The discharge stream from the passageway 148 arches hugging the cylindrical wall 153, and if the air vent is not placed out of the region of liquid flow, it tends to discharge liquid during priming which is undesirable.

A filling cock 159 may be disposed at the top of the main pump casting for the introduction of the charge of priming liquid. A pressure gauge 160 is connected to the top of the discharge chamber or separator 147 in position below the elbow fitting 157, and the gasoline tank 162, so that the said pressure gauge which is relatively fragile is not likely to be injured by the hose or objects which might brush across the top of the device. The discharge elbow 157 which is bolted to the top of the casting 114 is connected by a coupling 164 to a valved twin hose connection 165. This is a Y-shaped fitting having a shutoff valve disposed in each branch, so that each branch may be separately opened or closed. Protecting caps 167 suitably tethered by chains 168 are provided for each of the branch connections, said branch connections being provided with standard threads 25 for the coupling of discharge hose.

The intake to the pump is through a suction connection 169 shown in Figure 5. This comprises a cylindrical fitting having a clamping flange 170 for clamping the same in the opening 172 formed in the main body casting 114 at the top of the vertical leg of the intake trap 140. The inner end of the intake fitting 169 comprises a strainer 173 for catching any solid matter which would not readily pass through the pump. The outer end of the fitting 169 comprises a threaded nipple which is adapted to receive a standard hose coupling, such as 92, shown in Figure 1. The said nipple, when the pump is not in operation, is closed by the threaded cap 174 which performs the function not only of protecting the threads of the said nipple, but more particularly of preventing loss of liquid from the intake trap during transport of the pump. It is necessary that the pump have associated therewith the proper operating charge for producing suction; otherwise it is unable to raise liquid from the lower level.

The operation of the pump as a self-priming pump is as follows: The pump has a priming charge associated therewith. This normally consists of water trapped in the hollow pump body and impeller chamber below the bottom level of the intake connection 169. The intake trap is designed to retain a part of the liquid being pumped when the pump stops. In cold weather, the trapped water is drained out through the pet cock 177, and a tank of water with an adequate amount of anti-freeze material therein is either carried with the pump or the pump may be filled with a charge of water solution containing anti-freeze. When it is desired to put the mobile pumper to use, the unit, with full equipment as shown in Figures 1 and 2, is hitched to the rear bumper of an automobile. This may be done by manually raising the tongue of the unit and pulling it to the automobile or, alternatively, the automobile may be backed up to the unit, and the jaws 22, 23 clamped upon the bumper. Usually it is necessary to raise the tongue slightly from the position shown in Figure 2 in order to register the jaws with the bumper of the automobile. The chain or chains 26 with the snap hooks 21 are slung around the bumper and hooked back to provide a safety connection for

hitching the trailer bumper to the automobile. The standard 5 is then raised, and clamped in raised position. The operator checks over the equipment to see that everything is in place; the suction hose 83, the fire axe 180, the chemical extinguisher 73, and the necessary tools in the tool box 74. The pumper is then hauled to the place of use, and it may be disconnected from the rear bumper of the automobile and moved by hand to the desired place, or preferably it is left hitched to the bumper, and the standard 5 is dropped to a suitable level. Thereupon the operator may, if desired, start the engine in order to warm up the same. This may be accomplished either through the use of a hand crank 50 or preferably by an electric starter, a battery being carried at 182 in the battery box forward of the axle. Assume that the engine is now started. It idles, turning over the impeller 122 of the pump to warm up the engine. While all of the operations may be performed by one man, it will facilitate getting into operation to have several available. The canvas or other flexible cover 99 is released and rolled back into the position shown in Figure 1. The straps 87, 87 are loosened to release the suction hose 83. The top length of hose carrying the strainer is first released by lifting one end, for example the strainer end, from behind the fender 16, unfolding the hose out from under the cross bar 38 and out of the front saddle or bracket 16, whereupon the hose is freed, and if a single length suffices, the coupling 92 may be attached to the suction fitting 169, the cap 174 which serves to prevent the loss of liquid during transport of the vehicle being removed. If more than one suction length is necessary, the additional length 83 is coupled to the suction fitting 169 and then the terminal length 83 with the strainer 90 is coupled up, and the strainer dropped into the water of the source. The engine may now be speeded up in order to draw the air out of the suction line, and to prime the pump while the discharge hose is being coupled. Obviously, the engine may be started up after all the connections are made or at any intermediate stage. The priming charge will not be lost for the reason that the discharge shutoff valves 166 are closed during the operation of making the unit ready to throw water. The discharge hose, of which there may be sufficient length to run one long or two shorter lines, or if only a single fitting and single length of hose is to be employed, is coupled to the discharge fitting 165, the cap or caps 167 being unscrewed and removed. The hose, which is run out from the coil 96 and then from the box 42 to the proper length, is uncoupled at the nearest coupling in the continuous run of coupled length of hose, and the said coupling then attached to the discharge connection 165. Thereupon, as soon as the pump has produced the desired pressure, as shown on the gauge 160, the shutoff valve 166 is opened and by means of the hose and nozzle water may be thrown upon the fire. The indication of the gauge 160 is desirable in that it shows by sudden rise of pressure that the pump has primed and is ready to discharge water. This is true even with closed cutoff valves 166, since air pressure will not accumulate.

70 The engine 104 is designed to operate the impeller at a relatively high speed, preferably under a suitable automatic governor control. As an example, the engine herein illustrated is designed to operate at full load at a speed around 2800-3000 R. P. M. The pump is designed for operation at

that speed, and within any practical suction limit, to discharge 150 or more gallons per minute at approximately 100 pounds pressure at the pump.

When the impeller is first started up, liquid is drawn from the intake trap 140 through the intake passageway 134 at the center of the impeller, and discharged out both discharge passageways 148 and 150 into the separator. However, the impeller having discharged liquid is unable to keep the same from running back and very quickly an orderly recirculation of liquid returning through the passageway 150 and being mixed with air in the impeller chamber and discharged through the main discharge passageway 148 sets up the orderly evacuation of air from the intake side of the pump and the discharge of the same through the separator. As liquid from the bottom of the separator returns into the top of the impeller 122, the liquid is churned up with air and discharged as a mixture out the throat 149 and passageway 148 substantially tangentially of the circular wall 153. As the end wall 143 forms a deflector, the return stream of liquid which is already partly freed of air will be thrown out of the plane of the impeller and the discharge passageways 148 and 150 over the left as shown in Figure 5 in substantial registry with the part indicated at the reference numeral 146 and out of register with the hood 155 which faces against the stream of the liquid discharged through the passageway 148. The stream of mixture is guided in a generally helical path. Air tends to be forced out by the inertia effect or centrifugal effect of the liquid which tends by its density to move to the outermost layers, forcing the gas inwardly and freeing the same by centrifugal stratification. Likewise, the body of liquid has a free surface in the separator space 147 where gas is freed by gravity and it escapes through the discharge elbow connection 157 and out of the vent 158. As heretofore explained, an air valve connected with the top of the separator chamber 147 may be located at any convenient place, but the vent 158 as shown is connected to the discharge elbow connection 151 where air tends to accumulate and the discharge of air is not obstructed by liquid. The specific location of the air vent is otherwise not critical. A suitable connection is indicated at 184 in Figure 7 in line with the filler cock 159 which is mounted in a threaded socket 183.

Since the valves 166 are closed, unless provision were made for evacuating the air which is pumped out of the suction pipe, the speed of priming would be greatly reduced, and priming might even be prevented. Furthermore, the shutoff valves 166 are desirably closed during the time that the discharge hose is being connected, in order that the pump may be running to prime itself while the discharge hose is being connected, and thus reduce the amount of time required to put the unit into operation, that the priming liquid be not lost and to facilitate making the hose connections.

The pump is simple to service. The suction hose may easily be uncoupled and replaced in the mounting provided therefor. The strainer 173 may readily be cleaned out. The packing gland is simple and effective and may easily be lubricated and serviced. The unit is designed for operation and upkeep by amateur firemen.

It will be observed that the center of gravity of the trailer unit is relatively low for the sake 75

of stability, and when all of the equipment is loaded ready for transport, the center of gravity is slightly forward of the axle for ease and safety in hauling either by power vehicle or by hand, and when the discharge and suction hose are unloaded, the center of gravity is shifted forward further, to insure stability of the unit while pumping liquid. The center of gravity of the loaded unit is substantially no higher than that of a standard commercial automobile.

I do not intend to be limited to the details shown and described, but intend to include such equivalents as are known to those skilled in the art and are permitted within the appended claims.

I claim:

1. In a motor fire pump, a direct connected motor pump unit comprising a multi-cylinder engine having a crank case with a crankshaft, a self-priming centrifugal pump with an impeller casing and an impeller shaft fixed to the end of the crankshaft, said pump comprising a main unitary body having an intake trap, and a separator formed therein, and comprising a front 25 plate for the impeller casing, a bell bracket having an integral back plate for the impeller casing, and a coupling flange for connecting the same to the main pump body, and having a mounting flange clamped to the crank case.

30. 2. The unit of claim 1 having a fuel tank mounted on the engine between the engine and the pump over the bell bracket.

3. The unit of claim 1 wherein the separator portion of the main pump body carries a discharge elbow at its upper end, said elbow having shutoff valve means, a fuel tank mounted on the rear end of the engine above the bell bracket, and a pressure gauge at the top of the separator between the discharge elbow and the fuel tank.

4. A self-priming pump comprising a main body casting and a back plate member, said main body casting comprising a generally cylindrical barrel portion having an integral front plate 45 with a central inlet opening for defining an impeller chamber, a separate bell bracket and back plate member extending into said barrel portion and forming a closure for the impeller chamber, an impeller in the chamber and a shaft therefor extending through the back plate member, said body casting having walls defining a rear circular drumlike portion and a forwardly offset portion with an outlet opening in said offset portion, a pair of discharge passageways between the impeller chamber and the drumlike portion of the separator, one of said passageways being a main discharge passageway and extending substantially vertically and substantially tangentially of both the impeller chamber and of the drumlike portion, the other passageway being an auxiliary passageway through which liquid returns from the separator to the impeller chamber during priming and through which liquid is discharged from the impeller chamber during liquid pumping, said second passageway opening from the impeller chamber into substantially the bottom part of the drumlike portion.

5. The pump of claim 4 wherein the two passageways lie in substantially the same plane and the drumlike portion of the separator has an upwardly extending deflecting wall for deflecting the stream discharged from the main passageway out of the plane of the auxiliary passageway.

6. In a pump of the class described, a main pump body comprising a single hollow casting

comprising walls defining an impeller chamber having a central inlet and a pair of peripheral discharge passageways, namely, a main passageway and an adjacent auxiliary passageway lying in substantially the same plane, walls defining a separator having a drumlike portion, the main discharge passageway opening generally tangentially from the impeller chamber along the curved wall of the drumlike portion whereby during priming the discharge stream of mixture tends to follow the curved walls of the drum in an arched pathway, the walls of said drumlike portion comprising a head member against which the said stream of mixture is adapted to react to throw the same out of register with the auxiliary discharge passageway.

7. The pump body of claim 6 further characterized by the auxiliary discharge passageway opening into said drumlike portion at substantially its lowest level and the walls of said auxiliary passageway comprising a hood extending substantially horizontally to prevent air striking down through said auxiliary passageway.

8. The pump body of claim 6 further characterized by the separator chamber having walls providing an offset portion extending forwardly from the drumlike portion, and walls defining an intake trap of approximately the full width of the separator chamber disposed below said forwardly extending portion and opening at its lower end into said central inlet of the impeller chamber and having an opening for a suction connection in its front face near its upper end.

9. A pump comprising a main body casting comprising a hollow oblong body with its major axis vertically and having a main front wall and a main back wall, internal walls comprising an upper horizontally extending wall joining the upper part of the main front wall, a lower horizontally extending wall forming the lower part of the back wall and a vertically extending internal wall joining said horizontally extending walls, said internal walls dividing the main part of the body casting into two elbow shaped chambers, the upper chamber being a separator and the lower chamber being an intake trap, said casting comprising walls defining a circular impeller chamber below the vertical leg of the elbow shaped separator and having main and auxiliary passageways providing communication between the separator and the periphery of the impeller chamber, said impeller chamber having a central intake opening communicating with the horizontal arm of the intake trap, the horizontal arm of the separator having a discharge outlet connection and the vertical arm of the intake trap having an intake fitting.

10. In a self-priming centrifugal pump, a hollow pump body having main front and back vertical walls and having an internal wall extending horizontally, then down vertically and again horizontally at a lower level to divide the hollow body into two elbow shaped chambers, namely, an intake trap and a separator above the trap, said trap having a vertical leg under said first horizontal run of the internal wall and an opening near the top of said vertical leg, and a combined strainer and intake fitting for said opening, said fitting comprising a flange for attachment to the wall about the opening, a perforated tubular extension projecting horizontally into the top of the separator, and a threaded nipple for connection of a suction hose extending forwardly from the flange.

11. The combination with claim 10 of a dis-

charge fitting at the top of the separator, a valve for said discharge fitting for closing off the discharge of the pump, and a cap for closing the intake fitting to prevent loss of liquid trapped in the pump.

12. The combination with claim 10 of an elbow shaped discharge fitting extending vertically from the top of the separator and having a shutoff valve in its horizontal portion, and an air vent for venting air from the top of the separator when the said shutoff valve is closed to permit the pump to prime.

13. An integral unitary hollow pump body casting for a centrifugal pump comprising walls for enclosing functional chambers, said chambers comprising an impeller chamber of generally cylindrical form with a central inlet and peripheral discharge, an L-shaped inlet trap the lower end of which communicates through said inlet with the impeller chamber, and the upper end of which has a suction connection opening to the outside of the body casting, and a separator chamber of inverted L-shape with its lower end communicating with the impeller chamber through said peripheral discharge and the upper horizontal portion of said separator having a discharge connection opening to the outside of the body casting, there being an internal Z-shaped wall between and common to said trap and said separator.

14. The priming body of claim 13 wherein the vertical portion of the separator chamber is of approximately cylindrical shape with its axis horizontal and the rear external wall of the body forms a head for said chamber, and wherein the peripheral discharge of the impeller chamber comprises a generally vertically directed throat opening into the separator adjacent said head, whereby the stream of fluid discharged through said throat opening is crowded axially by said head to cause it to move out of the vertical plane of the discharge throat.

15. In a pump of the class described, a pump body comprising an impeller casing having an impeller which substantially sweeps the inner peripheral wall of the casing, a separator comprising a substantially drum shaped chamber disposed above the impeller casing with its circular axis horizontal, a substantially tangential main discharge passageway extending upwardly from the side of the impeller casing in substantially the plane of the impeller, and substantially tangential to the inner sidewall of the separator chamber, a priming and secondary discharge passageway adjacent the main passageway opening into the drum shaped separator chamber at substantially the bottom of the same, said latter passageway also lying in substantially the plane of the impeller, said separator chamber having an end wall adjacent the discharge path of liquid from the main discharge passageway, which wall is inclined upwardly toward the plane of the main discharge passageway whereby the stream of liquid issuing from the main discharge passageway and flowing on the curved wall of the separator is crowded in an axial direction out of the plane of the opening of the priming passageway in the chamber.

16. In a self-priming centrifugal pump, a pump body comprising a generally drumlike impeller casing and a superposed generally drumlike separator casing, said casings having their axes of curvature substantially parallel and horizontal, the impeller casing having an impeller therein rotatable on a horizontal axis and having a sub-

stantially tangential main discharge passageway and a priming passageway both opening into the separator in substantially a common plane transverse to the axis of the separator, the main discharge passageway having its outer wall substantially tangential to the side wall of the separator to discharge liquid tangentially along the arched circular separator wall to separate air out of the liquid during priming, the priming passageway opening into the bottom part of the separator chamber, said drumlike separator casing having transverse wall lying closely adjacent the opening of the main discharge passageway whereby the stream of issuing liquid as it spreads out on the circular arched wall is crowded by reaction against said transverse wall out of the

5 plane of the opening of the priming passageway.
17. A bracket and backplate member comprising a cylindrical pluglike body forming a backplate for an impeller casing, and having a cylindrical surface for seating in said casing, and a clamping flange for clamping the member to the casing, a gland socket on said plug member, a mounting ring at the opposite end of the bracket, walls extending between said ring and said plug 10 to connect the same, a transverse web joined to said walls and disposed between said ring and said gland socket, said web having a central threaded opening for receiving a threaded gland follower sleeve.

HARRY E. LA BOUR.
